Attorney

UNITED STATES PATENT OFFICE.

EMIL F. BUSSE, OF JEROME, ARIZONA.

HAMMER.

1,387,920.

Specification of Letters Patent. Patented Aug. 16, 1921.

Application filed February 15, 1921. Serial No. 445,200.

To all whom it may concern:

Be it known that I, EMIL F. BUSSE, a citizen of the United States, residing at Jerome, in the county of Yavapai and State 5 of Arizona, have invented a new and useful Hammer, of which the following is a specification.

This invention relates to hammer constructions, it being the primary object of 10 the invention to provide a hammer head having a portion thereof formed of fibrous material whereby the hammer may be employed as a mallet.

A further object of the invention is to 15 provide a hammer of this character wherein the fibrous material may be readily and easily replaced, when the same becomes worn beyond use.

A still further object of the invention is 20 the provision of nail setting means, whereby the operator may readily and easily position a nail, with the tool.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, may be made within the scope of what is claimed, without departing from the spirit of the invention.

Referring to the drawing:—

35 Figure 1 is a side elevational view of a hammer constructed in accordance with the present invention.

Fig. 2 is a sectional view taken on line 2—2 of Fig. 1.

40 Fig. 3 is an end elevational view of the hammer head.

Referring to the drawing in detail, the reference character 5 designates the handle of the hammer and the reference character 45 6 designates the head thereof, and which forms the important feature of the invention.

A groove is formed in one of the side faces of the hammer head, the groove being 50 provided throughout the width of the head,

and as shown the walls of the groove taper toward the handle portion of the tool.

As clearly shown by Fig. 2 of the drawing, the walls of this groove are inclined toward the outer edges thereof to receive the block 55 of fibrous material indicated by the reference character 7, the edges thereof being also inclined so that the fibrous material may be slid into position from the outer extremity of the tool, and held against displacement 60 by the coöperation of the walls and side edges of the fibrous block 7.

A suitable opening is formed in the fibrous block 7, which opening registers with an opening in the head proper, to accommodate 65 a securing element such as a screw indicated at 8, which screw may be positioned in the wooden handle 5 of the tool to further insure against the block 7 becoming dislodged from its position in the head, and 70 at the same time insuring against the head becoming loose from the handle.

At the outer end of the tool, the fibrous block 7 is provided with an opening which extends to the outer edge of the tool, and 75 which opening registers with the cut out portion 9 of the hammer head, the cut out portion 9 being of a size to accommodate the usual nail head, while the opening in the fibrous block 7 and which is indicated by 80 the reference character 10 will accommodate the shank portion of a nail.

From the foregoing it is obvious that a nail may be positioned in the cut out portion 9, where the same will be supported by 85 the head, and an operator may, while the nail is in this position, readily position the nail without the necessity of holding the nail while the same is being positioned.

It is also obvious that the fibrous block 7, 90 which may be formed of leather or other tough material will protect a chisel handle against damage by the hammer head, and the hammer may be efficiently employed as a mallet.

Having thus described the invention, what is claimed as new is:—

In a hammer, a head having a groove formed in one of the side faces thereof, the groove tapering toward one end of the head, 100

the walls of said groove being inclined, a block of fibrous material having inclined side edges and tapering to conform to the taper of the groove, said block adapted to be positioned in the groove, means for securing the block within the groove, and said block having a cut out portion formed at one end thereof to accommodate a nail.

In testimony that I claim the foregoing as my own, I have hereto affixed my signature 10 in the presence of two witnesses.

EMIL F. BUSSE.

Witnesses:

GEO. L. BARNETT,
MARTIN A. MEDARIS.
